UNITED STATES PATENT OFFICE.

GEORGE O. DRAPER, OF HOPEDALE, MASSACHUSETTS, ASSIGNOR TO THE DRAPER COMPANY.

STEP FOR SPINDLES.

SPECIFICATION forming part of Letters Patent No. 641,001, dated January 9, 1900.

Application filed May 22, 1897. Serial No. 637,705. (No model.)

To all whom it may concern:

Be it known that I, GEORGE OTIS DRAPER, of Hopedale, county of Worcester, State of Massachusetts, have invented an Improvement in Spindle-Supports, of which the following description, in connection with the accompanying drawings, is a specification, like letters on the drawings representing like parts.

Heretofore it has been customary to restrain the rotation of bearings in a bolster case or support by or through pins or projections carried by the support and entering notches or spaces of the bearings, and especially this class of bearings are used when united by or through a screw-thread. In this invention I have aimed to do away with the means heretofore employed for restraining the rotation of the bearings and I have so made them that they will be self-retaining in substantially the position they may be left after the adjustment of the bearings without the use of the usual extra parts.

Figure 1 of the drawings represents a spindle, a bolster-case, a bolster, and a step embodying my invention. Fig. 2 shows the step detached.

The rail A, the bolster-case B, secured to the rail by or through a nut B', and the spindle C, having a sleeve-whirl C', and the bolster D, mounted loosely in the bolster-case and surrounded, as herein shown, by a packing d and threaded at its lower end internally, are and may be all as usual.

My improved step presents at its upper end the usual screw-thread e to fit the hole at the lower end of the bolster; but the lower end of the step is quite novel, it being convexed externally, as at e', and slotted, as at e², the said slots, as herein represented, being two in number to divide the lower end of the step into four substantially equal arms or feet, which are free to yield somewhat as they are forced into the bore of the bolster-case, they thereafter acting frictionally to restrain the rotation of the step in the bolster-case. This step has a shoulder e³, upon which rests a spring e⁴, which acts by pressure upon the lower end of the bolster to restrain the rotation of the bolster independently of the step.

In this class of spindle-bearings the proper

fit between the tapered lower end of the spindle and the tapered interior of the bolster is maintained by taking out the spindle at times and turning the bolster more or less on the 55 step, thus raising or lowering its interior surface to contact properly with the tapered surface of the spindle.

By splitting the lower end of the step and making it so that in its normal condition the 60 diameter of the lower end of the step through its convex portion e' is a little larger than the diameter of the bore in the bolster which is to surround the said step it is possible to push the said step down into the bolster and have 65 it retained there frictionally against any possibility of rotation in the bolster-case during the operation of the spindle; but by engaging the bolster, the bearings being removed, and turning the same with a force sufficient to 70 overcome the normal pressure of the spring the bolster itself may be readily turned on the step, to thus adjust it vertically with relation to the step to fit the taper of the pintle of the spindle.

This invention is not limited to any particular number of slits in the step, as the lower end of the said step may be cut into two or more segments.

The bolster and its connected step and 80 spring may be readily withdrawn from the bolster-case by a strong pull, and the use of the pin heretofore employed is completely done away with.

It will be noticed that the spring acts by 85 friction to restrain the movement of the bolster instead of using upturned ends and notches, as has been customary.

I am aware that spindle-steps have been notched and that a pin carried by the bolster-case has entered said notch to restrain the step from rotation with the spindle. Such construction, however, results in the wasting of considerable time when the step is being put into the bolster-case, for the slot has to 90 be put accurately upon the pin, thus making it slow and difficult to assemble the parts. A slotted step held in position by a pin interferes with the movement of the yielding parts of the bolster above the step, and the slot-and-pin connection acts unevenly, it operating 95 differently on one side of the case than upon 100

the other side thereof. To prevent a high-speed spindle from vibrating, it is necessary that the bearings above the step move freely, and anything which interferes with such freedom of movement is more or less detrimental. In my invention, however, where the step has a series of yielding arms or feet which may be compressed as the step is forced into the bolster-case, the difficulties heretofore attending the use of the slotted step and pin are obviated.

Having fully described my invention, what I claim, and desire to secure by Letters Patent, is—

15 1. A spindle-step made substantially spherical at its lower end and split as at e^2 to form a series of stiff yet yielding arms e' , combined with a bolster-case into the lower end of which the said step is fitted, the said arms 20 being compressed as the step is forced into the bolster-case, the said arms being retained in the bolster-case frictionally against rotation, substantially as described.

2. A bolster-case, and a bolster therein, 25 threaded at its lower end, combined with a step provided at its upper end with a thread to engage the threads of the bolster, and slotted at its lower end to thereby constitute yielding feet or arms which are adapted to

be held frictionally in the opening of the bolster-case, substantially as described. 30

3. A bolster-case, and a bolster therein threaded at its lower end, combined with a step provided at its upper end with a thread to engage the threads of the bolster and slotted at its lower end to thereby constitute yielding feet or arms which are adapted to be held frictionally in the opening of the bolster-case, and a spring interposed between a shoulder on the said step and the lower end 35 of the said bolster, to operate, substantially as described.

4. A bolster-case, a bearing mounted therein loosely and having an attached step, said step being slotted at its lower end to present 40 yielding arms or feet, said arms or feet being compressed when forced into the bolster-case, they thereafter acting frictionally against the interior of said case to prevent rotation of the step with the spindle, substantially as de- 45 scribed.

In testimony whereof I have signed my name to this specification in the presence of two subscribing witnesses.

GEORGE O. DRAPER.
